RIBBED SWIMMING POOL

Ezra L. Culver, Florence, Ala.

Original application February 9, 1956, Serial No.
D. 40,100. Divided and this application October 10,
1956, Serial No. 43,496

Term of patent 14 years

(Cl. D34—5)

FIG. 2.

FIG. 3.

FIG. 5.

FIG. 4.

This is a division of application Ser. No. D. 40,100, filed February 9, 1956.

I claim:

The ornamental design for a ribbed swimming pool, as shown.
